(57) **CLAIM**

I claim the ornamental design for a under cabinet lighting device, as shown and described.

DESCRIPTION

FIG. 1 is a front perspective view of the device.

FIG. 2 is a rear perspective view of the device.

FIG. 3 is a front view of the device.

FIG. 4 is a rear view of the device.

FIG. 5 is a right side view of the device. The left side view is a mirror image of the right side view.

FIG. 6 is a top view of the device; and,

FIG. 7 is a bottom view of the device.

Any broken line(s) shown are for illustrative purposes only and form no part of the claimed design.
